US0D1063479S

(12) **United States Design Patent** (10) **Patent No.:** **US D1,063,479 S**
(45) **Date of Patent:** **** Feb. 25, 2025**

(54) **CONTAINER OF A FRENCH PRESS**

(71) Applicant: **Miir Holdings, LLC**, Seattle, WA (US)

(72) Inventor: **Bryan Pape**, Seattle, WA (US)

(73) Assignee: **Miir Holdings, LLC**, Seattle, WA (US)

(**) Term: **15 Years**

(21) Appl. No.: **29/877,919**

(22) Filed: **Jun. 13, 2023**

Related U.S. Application Data

(63) Continuation of application No. 29/802,334, filed on Aug. 4, 2021, now Pat. No. Des. 1,009,544.

(51) **LOC (15) Cl.** **07-01**

(57) **CLAIM**

The ornamental design for a container of a french press, as shown and described.

DESCRIPTION

FIG. 1 shows a perspective view of the container of a french press.

FIG. 2 shows a front, elevation view of the container of a french press.

FIG. 3 shows a rear, elevation view of the container of a french press.

FIG. 4 shows a right, elevation view of the container of a french press.

FIG. 5 shows a left, elevation view of the container of a french press.

FIG. 6 shows a top, plan view of the container of a french press; and,

FIG. 7 shows a bottom, plan view of the container of a french press.

The broken lines in FIGS. 1-7 show portions of the container of a french press that form no part of the claimed design.

1 Claim, 6 Drawing Sheets
